UNITED STATES PATENT OFFICE.

DAVID S. KENNEDY, OF BROOKLYN, NEW YORK, ASSIGNOR TO MERGENTHALER LINETYPE COMPANY, A CORPORATION OF NEW YORK.

TYPOGRAPHICAL COMPOSING MACHINE.

Application filed February 2, 1925. Serial No. 6,173.

My invention relates to typographical composing machines, such as linotype machines of the general organization represented in Letters Patent of the United States to O. Mergenthaler No. 436,532, wherein circulating matrices are released by escapements from a channeled magazine in the order in which their characters are to appear in print, and then assembled in line, the composed line transferred to the face of a mold, the mold filled with molten metal to form a slug or linotype against the matrices which produce the type characters thereon, and the matrices thereafter returned through a distributing mechanism to the magazine from which they started. In these machines, as the matrices are released from the magazine, they pass into a so-called assembler entrance provided with a series of vertically disposed partition plates which guide and direct the matrices upon a constantly driven inclined belt discharging into the assembler. These partition plates are fastened at their rear edges to the back plate of the assembler entrance and extend to the upper edge thereof, being spaced apart at their upper ends to align with certain of the magazine channels. Heretofore, during composition, the upper portion of the entrance back plate has formed a direct continuation of the magazine bottom plate, so that the matrices when released from the magazine would enter the assembler entrance without hindrance. With this arrangement, however, unless the parts are specially designed for the purpose, it is not feasible to handle matrix fonts above a certain thickness, for the reason that the thicker matrices of such fonts, due to the varying angles at which the magazine channels are disposed, fail to leave the magazine and become wedged against the entrance partition plates.

It is the primary object of my invention to obviate this difficulty and provide means whereby the standard magazine and assembler entrance will be adapted to handle relatively thicker matrices in the usual way. To this end, the delivery end of the magazine, instead of registering directly with the assembler entrance, as heretofore, is spaced therefrom a sufficient distance to allow the lower projecting ears of the matrices to pass out of the magazine channels before the bodies of the matrices are engaged by the entrance partition plates, and in the space

thus created, there is located a ribbed plate which bridges or closes the gap between the bottom plate of the magazine and the back plate of the entrance and which acts to support and guide the matrices in the proper manner as they pass from the magazine into the assembler entrance. According to this arrangement, the thicker matrices, which would otherwise be arrested by the entrance partition plates, are afforded greater clearance as they leave the magazine and are allowed to pass uninterruptedly to the assembler belt. In machines of the class presented in my prior Patent No. 1,386,786, wherein the magazines are pivoted on separate axes adjacent the corresponding distributors, the use of such a bridge plate is further advantageous, since it permits the protruding escapement plungers of the lower magazine to clear the entrance back plate when that magazine is raised above the entrance for inspection or removal.

In the accompanying drawings, I have shown my improvements merely in preferred form and by way of example and as applied to a particular kind of machine. It will be obvious, however, that they may be embodied in other forms and applied to machines of other kinds without departing from the spirit of my invention. Generally speaking, I desire it to be understood that I do not wish to limit myself to any specific form or embodiment, except in so far as such limitations are set forth in the claims.

Referring to the drawings:

Fig. 1 is a vertical section, partly in elevation, taken through the upper part of the assembler entrance and the lower end of a magazine, showing the application of the present improvements;

Fig. 2 is a front elevation, showing a portion of the assembler entrance with its front cover plate removed;

Fig. 3 is a section taken on the line 3-3 of Fig. 2, showing the relative location of the assembler partition plates and magazine channels in connection with the interposed bridge plate;

Fig. 4 is a view similar to Fig. 3; taken at the opposite side of the magazine; and

Fig. 5 illustrates a modification.

In the embodiment shown, the matrices X are stored according to font in the two standard magazines A and B, which are mounted so that either may be brought into operative

relation to the assembler entrance C, the latter comprising, as usual, the back plate C¹, cover plate C², and the series of intervening upright partition plates C³. These partition plates C³ are fastened edgewise to the back plate C¹ and are spaced apart at their upper ends so that matrices escaping from the magazine will be guided and directed thereby onto the assembler belt C⁴.

10 In the present instance, the magazines A and B are of the regular trapezoidal shape, each being provided on the inner faces of its two side plates with series of ribs a presenting sets of opposing grooves a¹, which converge from the upper to the lower ends thereof and provide channels wherein the projecting ears X¹ of the matrices engage. The escapement mechanisms employed to effect the release of the matrices from the 20 respective magazines are mounted in the escapement bars or frames A¹, B¹, each escapement unit consisting, as usual, of the verge or rocking lever A², the actuating plunger A³, and the alternately acting pawls A⁴. The actuating plungers A³ are operated from a keyboard mechanism (not shown) through the customary pivoted levers D. The parts so far described, except as hereinafter specified, are or may be the same 30 as shown in my prior Patent No. 1,386,786, to which reference may be had if desired.

Inasmuch as the invention is applicable to a single magazine, it will be described in detail in connection with the magazine A only, that being the one shown in operative position in the drawing.

Owing to the convergence of the magazine channels, the matrix columns stored in one side of the magazine will be disposed at certain angles to the partition plates C³ (see Fig. 3), while the matrix columns stored in the opposite side of the magazine will be disposed at reverse angles to the partition plates (see Fig. 4). Hence, in a font of the size indicated, the thicker matrices, say, of columns 1, 2, 3, 4 and 5, would contact with the upper ends of the partition plates C³, if the latter extended, as heretofore, close up to the delivery end of the magazine, and 40 would consequently be prevented from leaving the magazine grooves, as before pointed out. According to the present invention, a bridge plate E is interposed between the upper end of the entrance back plate C¹ and the bottom plate of the magazine A (see Fig. 1) and is made wide enough to enable the lower projecting ears of the matrices to pass out of the magazine channels before the matrices themselves engage the partition plates. In the embodiment shown, the bridge plate E is fastened to the escapement frame A¹ and is formed on its upper edge with a series of ribs E¹ and intervening notches E², the said ribs and notches registering with 50 and forming continuations of the magazine ribs and grooves a and a¹, respectively. As will be noted, the entrance partition plates C³ are arranged in vertical alignment with only certain of the ribs E¹, there being fewer partition plates than there are magazine 70 channels, as customary. Some of the notches E² are wider than the corresponding magazine channels, preferably those adjacent and to the right of the partition plates C³ (Fig. 3) and also those adjacent and to the left of other partition plates (Fig. 4). As a result of the foregoing arrangement, and since the leading ends of the matrices will be free as they strike the partition plates C³, the latter will merely straighten them up or cam them 80 facewise and allow them to escape uninterrupted to the assembler belt C⁴. While desirable, it is not absolutely essential that the ribs of the bridge plate E correspond in number and arrangement to the magazine 85 ribs a. Thus, those ribs with which the partition plates C³ register are the most important, since they serve, as intended, to prevent the matrices stored in the channels adjacent from catching behind the upper 90 ends of the partition plates before their side faces come under the control thereof. On the other hand, the other ribs are useful in preventing twisting or undue deflection of the matrices as they pass from the magazine 95 into the assembler entrance.

A corresponding bridge plate F secured to the escapement frame B¹ serves in the same capacity as the plate E when the magazine B is in operative position. 100

As before stated, the present invention has an additional advantage when applied to the type of multiple magazine machine described in my prior Patent No. 1,386,786 before mentioned, and wherein the magazines are pivoted near their upper ends so that the selected one may be swung into operative position. In other words, when the magazine B is provided with the bridge plate F (as shown in Fig. 1), the escapement 105 plungers B³ of that magazine will readily clear the entrance back plate C¹ when the magazine is raised above the entrance for removal, whereas without the bridge plate the plungers would strike the back plate 110 unless otherwise provided for. Instead of being carried by the escapement frame, as above described, the bridge plate may, as shown in Fig. 5, take the form of a ledge A⁶ protruding from the bottom plate of the 115 magazine. This and other modifications will readily suggest themselves to those skilled in the art and still be comprised within the scope of my invention.

Having thus described my invention, its 120 construction and mode of operation, what I claim and desire to secure by Letters Patent of the United States, is as follows:

1. In a linotype machine, the combination 125 of a matrix magazine, an assembler entrance of a

having its back plate spaced from the delivery end of the magazine, and a ribbed plate to bridge such space and forming a continuation only of the bottom plate of the magazine, leaving the top plate of the magazine unextended.

2. In a linotype machine, the combination of a matrix magazine, an assembler entrance having its back plate spaced from the delivery end of the magazine, an escapement frame, and a ribbed plate carried by the escapement frame to bridge such space, said plate forming a continuation only of the bottom plate of the magazine and leaving the top plate of the magazine unextended.

3. In a linotype machine, the combination of a grooved matrix magazine, an assembler entrance having its back plate spaced from the delivery end of the magazine, and a plate to bridge such space, the said bridge plate being formed on its upper edge with ribs aligned with the corresponding magazine ribs, and the said plate forming a continuation only of the bottom plate of the magazine and leaving the top plate of the magazine unextended.

4. In a linotype machine, the combination of a grooved matrix magazine, an assembler entrance having partition plates arranged to cooperate with the matrices as they escape from the magazine, and a bridge plate arranged between the delivery end of the magazine and the upper end of the assembler entrance, said plate being formed with notches registering with and forming continuations of the magazine grooves, certain of said notches adjacent the partition plates being wider than the registering magazine grooves, for the purpose described.

5. In a linotype machine, the combination of a grooved matrix magazine, an assembler entrance having a series of vertically disposed partitions, and a bridge plate arranged between the delivery end of the magazine and the upper end of the entrance back plate, the said bridge plate being formed with transverse ribs aligned with the partition plates and with intervening notches registering with the corresponding magazine grooves, and the said plate forming a continuation only of the bottom plate of the magazine and leaving the top plate of the magazine unextended.

6. In a linotype machine, the combination

of a plurality of matrix magazines interchangeable in position with each other, an assembler entrance having the upper end of its back plate spaced from the delivery end of the magazines, and plates carried by the respective magazines for bridging such space when a selected magazine is brought into operative position, said plates forming continuations only of the bottom plates of the respective magazines, leaving their top plates unextended.

7. In a linotype machine, the combination of a magazine, an assembler entrance having the upper end of its back plate spaced from the delivery end of the magazine to permit swinging of the latter above the entrance, and a plate for bridging such space when the magazine is in operative position, said plate forming a continuation only of the bottom plate of the magazine, leaving its top plate unextended.

8. In a linotype machine, the combination of a grooved magazine, an assembler entrance provided with a series of partition plates and having the upper end of its back plate spaced from the delivery end of the magazine, and a plate for bridging such space when the magazine is in use, the said bridge plate being formed on its upper edge with transverse ribs registering with the entrance partition plates and the corresponding magazine ribs, and the said plate forming a continuation only of the bottom plate of the magazine and leaving the top plate of the magazine unextended.

9. In a linotype machine, the combination of a grooved magazine, an assembler entrance provided with a series of partition plates and having the upper end of its back plate spaced from the delivery end of the magazine, and a plate for bridging such space when the magazine is in use, the said bridge plate being formed on its upper edge with transverse ribs registering with the entrance partition plates and the corresponding magazine ribs, and also formed alongside of said transverse ribs with notches of sufficient width to allow the matrices to be displaced laterally as they leave the magazine.

In testimony whereof, I have affixed my signature hereto.

DAVID S. KENNEDY.
